Term of patent 7 years

(Cl. D91—1)

FIG. 1

FIG. 2

FIG. 3

FIG. 4

FIG. 1 is a perspective view of a lawn sprinkler showing my new design;

FIG. 2 is a side elevational view thereof;

FIG. 3 is a top plan view thereof; and

FIG. 4 is a rear end elevational view thereof.

The essential features of my design reside in these features shown in full lines.

The end of the head member not shown is convex in shape and substantially plain except for the attached elements which are shown in dotted lines.

I claim:

The ornamental design for a lawn sprinkler, as shown and described.
